[57] CLAIM

The ornamental design for a knife holder, as shown and described.

DESCRIPTION

FIG. 1 is a left front perspective view of a knife holder, showing our new design;

FIG. 2 is a front elevational view thereof;

FIG. 3 is a rear elevational view thereof;

FIG. 4 is an elevational view of the left-hand end thereof, the right-hand end view being a mirror image of the figure shown;

FIG. 5 is a top plan view thereof, the rubber friction rollers being shown at the bottom of the inclined roller ramps; and,

FIG. 6 is a bottom plan view thereof.

The knife shown in broken line in FIG. 4 is included to show the environment and forms no part of the design.

FIG. 1.

FIG. 2.

FIG. 3.

FIG. 4.

FIG. 5.

FIG. 6.
